UNITED STATES PATENT OFFICE.

LEONADUS E. KARNES, OF SPRINGDALE, ARKANSAS.

DESIGN FOR A CLOTHES-PIN.

SPECIFICATION forming part of Design No. 31,290, dated July 25, 1899.

Application filed June 30, 1899. Serial No. 722,470. Term of patent 14 years.

To all whom it may concern:

Be it known that I, LEONADUS E. KARNES, a citizen of the United States, residing at Springdale, in the county of Washington and State of Arkansas, have invented and produced a new and original Design for a Clothes-Pin, of which the following is a specification.

The invention relates to a new and original design for a clothes-pin; and it has for its object to provide a design of this character that shall be both ornamental and useful.

The essential feature of the design resides in a clothes-pin provided with a central longitudinal coil and having approximately L-shaped arms extending in opposite directions from the ends of the coil and crossing at the bottom of the same and having hooks at their outer ends.

In the drawings, Figure 1 is a perspective view of a clothes-pin, showing my new and original design. Fig. 2 is a reverse plan view of the same.

Referring to the drawings, 1 designates a clothes-pin provided at its center with a longitudinal coil 2, and from the ends thereof extend reversely-arranged approximately L-shaped arms 3, having short transversely-disposed portions 5 and long longitudinal portions 6. The longitudinal portions 6 are arranged approximately parallel with the coil 2, and the inner portions of the L-shaped arms form a loop at the inner side of the coil. The L-shaped arms are provided at their outer ends with hooks 7.

What is claimed is—

The design for a clothes-pin herein shown and described.

In testimony that I claim the foregoing as my own I have hereto affixed my signature in the presence of two witnesses.

LEONADUS E. KARNES.
